UNITED STATES PATENT OFFICE.

EDWARD POHL, OF NEW YORK, N. Y.

SILK-THREAD-FINISHING MACHINE.

936,473.

Specification of Letters Patent. Patented Oct. 12, 1909.

Application filed November 13, 1908. Serial No. 462,523.

To all whom it may concern:

Be it known that I, EDWARD POHL, a citizen of the United States of America, and a resident of New York, county and State of New York, have invented certain new and useful Improvements in Silk-Thread-Finishing Machines, of which the following is a specification, reference being had to the accompanying drawings, forming a part thereof.

My invention relates to silk thread finishing machines, and particularly to machines for lustering and finishing silk threads by the application of a solution thereto, and in then drying and ironing the same.

In this class of machine it is common to pass the threads through a bath containing a finishing solution, and to then convey the threads over a suitable heated contact surface, whereby they are dried and ironed. Great trouble has been experienced in the past, in the use of this class of apparatus, in the deposit of solution, which has been carried over by the threads, upon the surface of the contact table. Furthermore, there is a tendency to the production of flattened threads and threads which are polished or ironed only part of the way around. This trouble has largely arisen from the fact that the threads are usually conveyed directly from the bath over the table so that they engage the table while thoroughly wet. To overcome this difficulty, I have attempted in the past to pass the threads initially through a drying chamber so as to partially dry them before they reach the table, but in order that this may be effective it is necessary either to pass them through a prohibitive length of chamber or else to run them so slowly as to render the operation of the apparatus too expensive to be practical.

In my present apparatus I convey the threads from the bath over a heated contact member, whereby I remove the surplus moisture therefrom without tending to dry or iron them to any degree;—from this point I convey the threads through an evaporating chamber wherein I dry the threads to a considerable extent, say, from 75% to 90%,—and thereafter I carry the threads over the ironing table, whereby they are ironed and polished. By this means when the threads reach the ironing table they are so nearly dry that there will be practically no deposit upon the ironing table at all; furthermore,

they will be dry enough to prevent the threads being flattened in the process of drawing them across the ironing table, so that they will be polished evenly thereby and retained in their round condition. I find that if the threads are not flattened the slight variation in tension thereupon tends to cause the threads to roll or twist more or less upon the ironing table, whereby they will be polished substantially equally all around. On the contrary, if they are thoroughly wet or moist when they reach the approach end of the table they become flattened and thereafter travel upon the table without this twisting or rolling movement, whereby one side only is ironed and polished. I preferably provide the member which is employed for initially removing the surplus moisture, with several contact surfaces, whereby the same may be turned from time to time so as to present new surfaces for contact with the threads, leaving the surfaces formerly used free to be cleaned. By this means I am enabled to run the machine continuously without stopping it for cleaning purposes.

I have found that a machine of this character can be run at a higher speed than has been possible heretofore, while the threads receive a better and evener polish and are more completely finished and lustered.

In order that my invention may be fully understood, I will now proceed to describe an apparatus constituting an embodiment of the same, having reference to the accompanying drawings illustrating the same, and will then point out the novel features in claims.

In the drawings: Figure 1 is a top view of the apparatus. Fig. 2 is a view in longitudinal vertical section therethrough, and Fig. 3 is a view in transverse section upon the line 3—3 of Fig. 2.

The apparatus comprises a bath 10, suitably supported upon a framework 11, a heated contact member 12 revolvably supported by means of arms 13 carried by the said framework 11, an evaporating chamber 14, and an ironing table 15 whose upper surface constitutes the main heated contact surface for the threads. A suitable system of heating pipes 16 arranged to receive steam, hot water, or the like, is provided for the purpose of heating the ironing table, the contact member 12, and the evaporating

chamber 14. The heated contact member 12 is preferably polygonal in cross-section, being here shown as of square form, whereby it is provided with four similar surfaces 5 which may be employed for contact with the threads. This member is held stationary during the normal operation of the machine and may be given a quarter turn from time to time in order to expose a fresh surface 10 for engagement with the threads and to free the surface formerly used, whereby it may be readily cleaned. I have shown the evaporating chamber as being formed partly by a depression 17 in the heated contact table 15 and partly by inclosing covers 18, two of 15 which are shown as provided, the said covers being hinged along the center line of the machine as at 19, whereby they may be lifted for the purpose of obtaining access to the 20 interior of the chamber 14 and returned into place again when the machine is in normal operation.

In operation silk threads 20 are introduced into the bath 10 and from thence are 25 carried over the heated contact member 12. The function of this heated contact member 12 is to remove the surplus material so that after the threads pass therefrom they carry only the quantity of finishing material 30 which it is desirable they shall permanently retain. Furthermore, though the threads are in no sense ironed by their contact with the member 12, they will be partially dried in the sense that practically all of the 35 surplus moisture will be removed; thereafter the threads will enter and pass through a chamber 14. In their passage through this chamber they will be considerably dried, so that when they finally reach the heated contact 40 surface of the table 15 the finishing material will be so far dry as to prevent there being any danger of any part of it being deposited upon the table, or of the threads being flattened by their engagement with the 45 table. After reaching this point they are drawn over the table and thereby ironed and finished, the said threads being taken up by suitable winding mechanism at some point

beyond the end of the contact table 15, as will be well understood. 50

What I claim is:

1. In apparatus for finishing and lustering silk threads, the combination with means for applying a finishing solution thereto, of a heated contact member over 55 which the threads are arranged to be drawn for the purpose of removing superfluous material therefrom, an evaporating chamber through which the threads are then arranged to pass, and an ironing table provided with a heated contact surface over 60 which the threads are arranged to be finally carried for the purpose of heating and ironing them.

2. A machine of the class described comprising a bath for containing finishing solution, an ironing table having a heated contact surface for receiving the threads, an evaporating chamber arranged between the bath and the heated contact surface of the 70 ironing table, and a contact member disposed between the bath and the evaporating chamber for removing the surplus moisture from the threads. 65

3. Apparatus of the class described provided with a heated contact table having a recessed portion at its approach end, and covers arranged above the recessed portion but out of line therewith, whereby a chamber is inclosed through which the threads 80 are arranged to pass prior to reaching the contact surface of the ironing table. 75

4. Apparatus of the class described, comprising an ironing table having a recessed portion at the approach end thereof, and 85 hinged covers arranged above the said recesses to form an evaporating chamber through which the threads are arranged to pass, the said covers being movable upon their hinges, whereby access may be had to 90 the interior of the chamber so inclosed.

EDWARD POHL.
